THREAD-GUIDE FOR TEXTILE-MACHINES.

1,204,294.

Specification of Letters Patent. Patented Nov. 7, 1916.

Application filed March 23, 1915. Serial No. 16,417.

To all whom it may concern:

Be it known that I, WILLIAM MARCROFT, a citizen of the United States, residing at Cranston, in the county of Providence and 5 State of Rhode Island, have invented certain new and useful Improvements in Thread-Guides for Textile-Machines, of which the following is a specification.

My invention is an improved yarn- or 10 thread-guide for use on spinning-frames or twisting-machines.

The object of my improvement is to provide a thread-guide adapted to receive a plurality of separate strands or fibers delivered thereto in the form of a flat tape or ribbon and to gather them into closely-associated, parallel relation preparatory to twisting them into the finished yarn or cord.

20 To this end my improved device consists essentially of a guiding-member or plate having a substantially flat face provided with a contracted yarn-receiving groove for confining and shaping the strands in their 25 proper relation. At one end of the groove is an open ring-like gatherer or eye arranged to direct the several strands into the forming groove, from the opposite end of which they deliver to the flier or ring-spinning 30 mechanism of the machine. By thus straightening and shaping the collection of associated strands in proper relation before they are twisted the individual strands are caused to lie more smoothly and evenly in 35 parallelism, without slack places or kinks in the fibers, and for this reason the finished yarn is greatly improved in quality and appearance.

The manner and means for carrying out 40 my improvement are fully described in the following specification, illustrated by the accompanying drawings, in which like reference characters designate like parts.

In the drawings: Figure 1 is a perspective view of my improved thread-guide; 45 Fig. 2 is a sectional view taken on the line X—X of Fig. 1, looking in the direction indicated by the arrow x; and Fig. 3 is a view showing the invention applied to use 50 in connection with a twisting-machine of conventional form.

Referring first to Fig. 3, R, R' and R² are the delivery rolls which draw the separate strands or yarns off from their indi-

vidual supply-spools or bobbins, not here 55 shown and B is the thread-board running longitudinally of the machine for supporting the thread-guides for the twister-bobbins or spools arranged in front and below. C is the ring-rail for supporting and traversing the spinning-ring D on which the ring-traveler d slides, and E is the twister-spindle for rotating the spool or bobbin S. The spindle E is usually driven from a belt or band passing around the "whirl" or 60 pulley e and the parts as above described are of substantially the same construction and arrangement on all spinning- and twisting-frames. Usually the thread-board B has secured to its front side a series of 65 hinged-plates P which carry wire pig-tails or guides p for the yarns drawing down from the delivery rolls R, etc. The pig-tails p are generally fastened in place by screws p' engaging threaded holes in the 70 plates P and my improved thread-guide can be applied to position on the plates P by means of these same screws. For this purpose I preferably form the thread-guide G with a foot or standard g adapted to set 75 down against the top of the wire pig-tail p, which is usually bent double in hairpin-shape, see Fig. 1, and a slot g' in the foot receives the screw p' to secure the parts together. As shown in Fig. 1, my improved 80 guide is preferably formed of sheet-metal with an arc-shaped upright or face-plate g² bent up from the foot g. If desired, however, the device might be made in two or more parts with the main guide-member 85 constructed of porcelain or some other wear-resisting material. The front face of the plate g² is scored with a longitudinal groove g³, preferably rounded on its bottom and 90 of the proper width and depth to adapt it 95 to confine the collection of strands or fibers in circular form as shown more particularly in Fig. 2. At its upper end the plate g² is bent forward in a right-angled projection or bridge-piece g⁴ formed with a central opening or eye g⁵ having its inner edge lying tangent with the bottom of the groove g³. Leading into the eye g⁵ is a flaring opening or slot g⁶ adapted to direct the strands into 100 place in threading them into the guide. Below the bridge g⁴ the groove g³ is flared 105 out to meet the sides of the eye g⁵, thus forming a funnel-like entrance g⁷ for the

contracted portion of the groove. In applying my improved guide to the thread-board of the twisting- or spinning-frame, the slot g' in its base allows for its adjustment inwardly or outwardly on the screw p' so that the lower end of the thread-groove g^3 can be set directly in line with the axis of the spindle E and the pig-tail p is then set to receive the yarns y as they emerge 10 from the groove at this point.

Having now described the structure and arrangement of my improved thread-guide in detail, its method of operation will next be explained: My new device is adapted for 15 use in all varieties of twisting and spinning operations, and is of particular advantage when a relatively large number of strands are to be combined in the ultimate twisted yarn. For instance, in spinning or twisting 20 strong, coarse yarns for automobile-tire fabrics, usually as many as eleven strands are twisted together to form the finished cord. Heretofore it has been found a difficult matter to deliver this large number of 25 strands to the ring-traveler or flier in smooth, even parallelism so that the yarns will lie evenly under the same tension in the twist. With my improved apparatus much greater uniformity of tension and smoothness 30 of lay of the associated strands is secured and consequently a stronger and evener yarn is produced.

Referring particularly to Figs. 1 and 3, the web or mat of strands y , y , etc., is carried 35 through the rolls R , R' , R^2 in flat relation and thence brought down and threaded through the guide-opening g^6 in the eye g^5 . From the eye g^5 the strands pass through the funnel-like mouth g^7 into the contracted 40 groove g^3 , and drawing down therethrough emerge at the bottom where they are guided and held from displacement by the pig-tail p . Thence they pass through the ring-traveler d and are twisted into the finished yarn 45 y' which is wound onto the bobbin or spool S through the rotation of the latter as the traveler revolves about the spool and traverses up and down between its ends. Heretofore, as before stated, only the pig-tail p 50 has usually been employed to guide the yarns as they draw from the delivery-rolls to the traveler d ; but with the present arrangement the pig-tail is auxiliary to the main guide G and its purpose is to prevent 55 the strands from whipping out of the guide-groove g^3 . Where only a pig-tail or other encircling eye is used to encompass the strands during the twisting operation their relation and the shape of their mass cannot 60 be controlled to attain parallelism and evenness of the individual units of the yarn.

My present improvement, as first explained, has for its object to provide a guide having a relatively long, narrow guiding-groove or channel which acts as a forming

die to bring the separate strands into proper relation and to iron out the kinks and slack places so that they may all be drawn into the twist under substantially the same tension. In this way the ultimate twisted yarn 70 will be formed with all of its strands lying smoothly and evenly in place so that "corkscrews" or "runners" as they are sometimes termed will be entirely eliminated. The term "runner" is applied to a loose strand 75 in the twisted yarn where it shows in a spiral or "corkscrew" raised above the surface of the other strands and such defects are often apparent in cords or yarns twisted in the usual manner. These runners, corkscrews, kinks and other loose strands not only detract from the appearance of the finished yarn, but also impair its tensile strength since when the yarn is subjected to strain the loose strand will not bear its 80 share of the tension and hence the whole cord is weakened. These defects are particularly serious in yarns intended for tire-fabrics since they not only spoil the smoothness and evenness of the weave, but also 85 detract from the strength of the fabric which is a most important consideration. With my improved guide the separate strands are ironed out and smoothed into 90 accurate parallelism during their passage through the forming-groove or die and their confinement in the groove also serves to clean them of any slivers, motes, slubs or other foreign matter which might otherwise 95 pass into the twisted yarn.

Various modifications might be made in the form and structure of my improved device or in the manner of applying it to use without departing from the spirit or scope 100 of the invention.

Therefore, without limiting myself to the exact embodiment herein shown and described, what I claim is:—

1. An improved yarn- or thread-guide for use on spinning, twisting or like machines comprising a plate-like member bent longitudinally into arcuate shape and formed with a contracted groove extending the length of its face and adapted to receive a plurality of associated strands drawing therethrough to confine them in closely-adjacent parallel relation. 110

2. An improved yarn- or thread-guide for use on spinning, twisting or like machines comprising a longitudinally curved plate 120 having a substantially flat face formed with a relatively narrow, shallow groove adapted to receive and confine a plurality of associated strands in parallel relation and means to secure said plate in position on the thread-board of the machine. 125

3. An improved yarn- or thread-guide comprising a foot-piece and a curved plate extending upwardly therefrom, with the convex face of said plate scored with a rela- 130

tively narrow, shallow groove adapted to receive a plurality of associated strands drawing therethrough to straighten them out in close, parallel relation preparatory to 5 twisting them into the finished yarn.

4. An improved yarn- or thread-guide comprising a slotted foot and a curved plate extending upwardly therefrom, with the convex surface of the plate scored with a 10 contracted groove adapted to receive a plurality of untwisted strands drawing therethrough and one end of said groove provided with a funnel-like mouth for directing the strands into the groove.
- 15 5. An improved yarn or thread-guide comprising a base member formed with an

upwardly-extending arcuate plate bent at its top to provide a right-angled bridge-piece, said bridge-piece formed with an open thread-eye and a relatively narrow, 20 shallow groove extending from the eye longitudinally of the convex face of the plate to adapt it to receive a plurality of associated fibers drawing through the eye and across the plate.

25 In testimony whereof I affix my signature in presence of two witnesses.

WILLIAM MARCROFT.
